UNITED STATES PATENT OFFICE.

CHARLES M. CLINTON, OF ITHACA, NEW YORK.

DESIGN FOR A COAT-HANGER.

SPECIFICATION forming part of Design No. 26,615, dated February 9, 1897.

Application filed December 16, 1896. Serial No. 616,931. Term of patent 3½ years.

To all whom it may concern:

Be it known that I, CHARLES M. CLINTON, of Ithaca, in the county of Tompkins, State of New York, have invented a new and original Design for a Coat-Hanger, of which the following, taken in connection with the accompanying drawing, is a full, clear, and exact description, reference being had to the accompanying drawing, in which I show an isometrical view of my design for a coat-hanger complete, this view being deemed sufficient to properly illustrate the design.

The leading feature of my design consists in a bracket having its body constructed in the form of a goose-neck, terminating in an eye at the top and laterally-extending arms from the lower portion provided with hemispherical pads or bodies, as shown.

a is the goose-neck body, terminating in the eye *b*, by which it may be suspended.

c are the laterally-extending arms, and *d* are the hemispherical bodies at the ends thereof.

The eye *b* is for supporting the hanger. The hemispherical bodies *d* engage with the coat or garment at the shoulder and the collar passes through the recess *e*, formed by the goose-neck shape of the body *a*. 25

Having described my invention, what I claim, and desire to secure by Letters Patent, is—

The design for a coat-hanger or similar article substantially as herein described and shown. 30

In witness whereof I have hereunto set my hand this 14th day of December, 1896.

CHARLES M. CLINTON.

In presence of—

MARY A. FRANKLIN,
HOWARD P. DENISON.
